UNITED STATES PATENT OFFICE.

HARRY M. PFLAGER, OF ST. LOUIS, MISSOURI, ASSIGNOR TO COMMONWEALTH STEEL COMPANY, OF GRANITE CITY, ILLINOIS, A CORPORATION OF NEW JERSEY.

TRUCK PEDESTAL.

Application filed March 10, 1927. Serial No. 174,271.

My invention relates to railway rolling stock and consists in an improved truck pedestal structure. It has been proposed to utilize anti-friction bearings for supporting the load on railway rolling stock journals, and where anti-friction boxes have been designed their width has necessarily been great enough to accommodate the rollers, balls, or other anti-friction elements surrounding the journal. In the ordinary bearing construction now in general use, the arcuate brass resting upon the upper surface of the journal does not extend laterally beyond the sides of the journal and the width of the journal box is only slightly greater than the diameter of the journal. As the pedestal legs ordinarily are only spaced far enough apart to accommodate the box between them, the substitution of anti-friction bearing boxes for the standard journal boxes would require the use of different pedestals which would add greatly to the expense of making the change from one type of box to the other. This would be particularly so where the desirable one-piece cast steel truck frame with integral pedestals is in use, as in such cases it would be necessary to scrap the entire frame and replace the same.

In my copending application Serial No. 174,272, filed March 10, 1927, I illustrate and describe a pedestal structure having parts which may be detached to provide a wider jaw.

The main object of my present invention is to provide a one-piece pedestal structure which will mount a standard journal box in the usual manner and is adapted to be modified so as to accommodate the wider anti-friction journal box.

In the accompanying drawings which illustrate my invention—

Figure 1 is in part a side elevation of, and in part a longitudinal vertical section through, a four wheel car truck, the frame of which includes an integral pedestal structure of the type mentioned above, and illustrating respectively the mounting of both types of boxes.

Figure 2 is a detail horizontal section taken on line 2—2 of Figure 1.

Figure 3 is a similar section taken on line 3—3 of Figure 1.

Figure 4 is in part a side elevation of, and in part a longitudinal vertical section

through, a separate pedestal, possessing similar features to the pedestals illustrated in Figure 1.

Figure 5 is a side elevation of a separate pedestal leg embodying similar features.

In the structure illustrated in Figure 1 the truck frame is of a familiar type having wheel pieces 1 connected by transoms 2 and including integral pedestal legs 3 spaced from each other a sufficient distance to accommodate a standard A. R. A. journal box 4 between them.

The side walls of each leg 3 extend longitudinally of the truck a somewhat greater distance than in the ordinary pedestal. The inner face of each leg is formed by a transverse web 5 and spaced from this web is a second web 6 also extending between the side walls of the pedestal. Webs 6 are so located that upon the removal of webs 5 and the portion of the side walls of the pedestal between webs 5 and 6, the distance between webs 6 will be sufficient to accommodate a roller bearing journal box of greater width as indicated at 7. 8 indicates the usual wear plates which may be applied to the legs irrespective of whether they terminate with webs 5 or webs 6.

The pads 14 to which plates 8 are bolted extend far enough away from the center line of the pedestal so that the flanges of the wear plates will be supported when the inner box-engaging elements 5 have been removed and the wear plates have been applied to the leg faces thereby formed. The pads 14 may be originally provided with holes 15 for accommodating the wear plate in either position.

By purchasing trucks constructed as shown on the righthand side of Figure 1, the railway company can utilize the present standard journal box, but if at any time in the future it is desired to change over to the anti-friction boxes, the inner portions of each pedestal leg may be machined away to produce a pedestal adapted to receive the wider roller bearing box. This enables the railway company to retain the desirable one-piece truck frame and pedestal structure without scrapping the old frame. Obviously my invention is adapted for use on six wheel trucks as well as on four wheel trucks and the economy of the use of my invention as mentioned above would be increased in the event of making the change to the wider

journal boxes when a six wheel truck was involved.

The same general features are included in the individual pedestal illustrated in Figure 5 which is adapted to be bolted or riveted to the truck frame. This pedestal includes the opposed vertical transverse webs 9 adapted to engage the sides of the standard journal box and the pedestal also includes 10 transverse webs 10 parallel with and spaced from webs 9 and adapted to engage the sides of a wider box after webs 9 and the adjacent portion of the side walls 11 have been cut away.

15 In Figure 5 I illustrate an individual pedestal leg element adapted to be secured to the truck frame and also provided with spaced transverse webs 12 and 13 adapted, respectively, to successively engage the walls 20 of journal boxes of different widths.

Obviously the details of construction of the devices described by me may be varied without departing from the spirit of my invention, and I contemplate the exclusive use 25 of such modifications as fall within the scope of my claims.

I claim:

1. A truck pedestal leg having a plurality of parallel surfaces spaced from each other 30 so as to successively engage the respective sides of journal boxes of different widths.

2. In a truck pedestal leg, a surface adapted to engage the side of a standard journal box to position the same, and a member 35 spaced from said surface and adapted to engage the side of a journal box of greater width than the standard journal box when the elements forming said surface are removed.

40 3. A truck pedestal leg comprising elements forming a journal box engaging surface, side walls extending at right angles to said surface, and a transverse member between said walls parallel with said surface 45 and spaced therefrom.

4. In a truck pedestal leg adapted to have a portion of its structure cut away to accommodate different sizes of journal boxes, a wear plate mounting pad on the side wall 50 of the leg extending toward the rear of said leg far enough to mount the wear plate in different positions, there being a plurality of holes in said pad for receiving a wear plate bolt when said plate is in different positions.

5. A truck pedestal having spaced legs 55 each of said legs having a plurality of faces respectively adapted to engage the sides of journal boxes of different widths.

6. A truck pedestal with spaced legs having elements adapted to embrace the sides of a standard railway journal box and also having members spaced from said elements and adapted to embrace the sides of an anti-friction bearing box when said elements are removed from said legs. 60

7. In a railway truck frame, an integrally formed wheel piece having spaced legs for receiving a standard journal box between them, said legs being of such extent longitudinally of the frame that a portion of each leg may be removed to accommodate journal boxes wider than a standard journal box. 70

8. In a railway truck frame, integral pedestals, each having integral elements adapted to embrace the sides of a standard journal box, and members in said pedestals spaced from said elements and adapted to embrace a wider journal box when said elements are removed. 75

9. In combination, a truck pedestal leg 80 having a plurality of elements spaced from each other so as to successively engage the respective sides of journal boxes of different widths, and a wear plate adapted to fit over either of said elements.

10. In combination, a truck pedestal having spaced legs, each of said legs having a plurality of elements respectively adapted to engage the sides of journal boxes of different widths, wear plates adapted to fit over said elements irrespective of the journal box 90 assembled therewith, and means for securing said wear plates to said legs.

11. In a truck pedestal leg, an inner transverse web for engaging a journal box, a second web, co-extensive with and spaced from said inner web, for engaging a journal box when said inner web is removed. 95

12. In a truck pedestal, spaced inner webs adapted to receive an A. R. A. journal box 100 between them, secondary webs co-extensive with and spaced from said inner web and adapted to receive a wider journal box between them when said inner webs are removed.

In testimony whereof I hereunto affix my signature this 7th day of March, 1927.

H. M. PFLAGER.
